UNITED STATES PATENT OFFICE.

RUDOLF KRAUS, OF NEW YORK, N. Y.

LINK DOOR-CHECK.

1,127,454.

Specification of Letters Patent.

Patented Feb. 9, 1915.

Application filed May 16, 1914. Serial No. 839,029.

To all whom it may concern:

Be it known that I, RUDOLF KRAUS, a subject of the Emperor of Austria-Hungary, and a resident of the city of New York, in the county of New York and State of New York, have invented certain new and useful Improvements in Link Door-Checks, of which the following is a specification.

The present invention relates to a door-check, and has for one of its objects to provide a simple and inexpensive device of this type which, when in a certain position, allows the door to be opened to some extent, and which, when in another position, serves to lock effectively the door to prevent the same from being opened even to a slight extent.

With these and other objects in view, which will more fully appear as the nature of the invention is better understood, the same consists in the combination, arrangement and construction of parts hereinafter fully described, pointed out in the appended claim and illustrated in the accompanying drawings, it being understood that many changes may be made in the size and proportion of the several parts and details of construction within the scope of the appended claim without departing from the spirit or sacrificing any of the advantages of the invention.

One of the many possible embodiments of the invention is illustrated in the accompanying drawings, in which:—

Figure 1 is a front elevation of a portion of a door and door frame to which a door-check constructed in accordance with the present invention is applied, the parts being in positions to hold the door closed; Fig. 2 is a section taken on line 2—2 of Fig. 1; and Fig. 3 is a front elevation of the device in a position so as to allow the door to be opened partially.

Generally speaking, the invention consists of a slotted link pivoted to either the door or the jamb, in combination with a stud pin that is pivotally attached to the other one of said two elements, means being provided for preventing the disengagement of said link and stud pin unless the door is entirely closed.

Referring now more particularly to the drawings, the numeral 1 indicates a portion of a door jamb, and 2 designates a portion of a door. A base plate 3 is secured rigidly in position upon the door jamb by screws 4,

or otherwise, said plate being provided with inwardly extending horizontal projections 5, having registering apertures 6 vertically extending therethrough. In these apertures are oscillatably mounted the pivot pins 7 of a link 8, that is made, for instance, of wire, and comprises two parallel legs 9, which are suitably spaced apart, whereby a longitudinal slot 10 is provided for a purpose herein-after to be described. This link is formed by bending the wire at its middle portion 11 back upon itself in parallel relation, its ends, forming the pivot pins 7, being bent at right angles to the longitudinal axes of said legs. Near the pivot pins 7 each leg is curved outward, as shown at 12, thereby forming a substantially circular enlargement of the slot 10.

A base plate 13 is fastened by screws 14, or otherwise, to the door 2 in alinement with the plate 3 above mentioned. The plate 13 has inwardly extending lugs 15, to which is pivoted by means of a vertically disposed pin 16, or otherwise, a stud pin 17, having upon its free end an enlarged round head 18, the circular enlargement of the slot 10 that is formed by bending out the portions 12 of the legs of the link being adapted to accommodate the head 18 of the stud pin, the diameter of the body of the stud pin being slightly smaller than the width of the slot 10. In the plate 13 is formed a screw threaded hole 19 for the reception of a thumb screw 20, preferably of the flat head type. The head 21 of this thumb screw is adapted to enter the slot 10 and to clamp down, as shown in Fig. 1 of the drawings, the link 8. In the plate 3 is formed a recess 22, in which the head 18 of the stud pin may be seated.

It is obvious that, while herein the link 8 has been described as being mounted upon the door jamb and the stud pin 17 upon the door, the positions of these elements may be reversed if desired. It is to be noted furthermore that, while the link 8 has been described as being formed of wire, the same may obviously be made of sheet metal by stamping or otherwise.

The operation of the device is as follows: In fastening the door by the use of the invention, so that the door may be opened to a limited extent for ventilation or for some other purpose, the door 2 is first closed, the link 8 having been swung previously backward into abutment with the door jamb.

The head of the stud pin is then seated into the recess 22 in the plate 3, and the link swung forward toward the door 2, whereby the head of the stud pin is passed through 5 the circular enlargement of the slot in said link. The door can now be opened to a limited extent, the body of the stud pin sliding in the slot 10 of the link, the head 18 of said pin preventing a disengagement there- 10 of from said link (Fig. 2). The door cannot be opened from outside since the slotted link cannot be disengaged from the stud pin unless the door is closed and the round head 18 of said pin is about to enter the recess in the 15 plate 3.

In order to disconnect the link from the stud pin for unfastening the door, the latter is closed and the link moved toward the door jamb into abutting position with the latter.

20 When it is desired to lock the door, the head of the stud pin is seated in the recess 22, the link swung into abutment with the base plate 13 and the thumb screw turned to engage the legs 9 of said link, thereby clamping the 25 same against the said base plate.

It is obvious that, inasmuch as the stud pin is pivoted to the door, the device can be

applied to all doors no matter what difference there be in the levels of the doors and the jambs thereof.

30 What I claim is:—

The combination with a door and door jamb, of a base plate having a recess fastened to one of said members, a slotted link pivoted to said plate, said slot being enlarged near the pivot of said link, a base plate fastened to the other one of said members, and a stud pin pivoted to the last named plate having an enlarged head adapted to be passed through the enlargement of 35 said slot, thereby seating the body of said pin in said slot, whereby the disengagement of said stud pin from said link is prevented unless the head of said stud pin is seated in said recess and said link is swung around its pivot to permit the head of said pin to pass through the enlargement of said slot.

Signed at New York, in the county of New York, and State of New York, this 13th day of May, A. D. 1914.

RUDOLF KRAUS.
